UNITED STATES PATENT OFFICE.

JAMES WHITELAW, OF ST. LOUIS, MISSOURI.

BLINDSTITCH SEWING-MACHINE.

1,287,157.

Specification of Letters Patent. Patented Dec. 10, 1918.

Application filed May 13, 1915. Serial No. 27,789.

To all whom it may concern:

Be it known that I, JAMES WHITELAW, a citizen of the United States, residing at St. Louis, in the city of St. Louis, State of Missouri, have invented certain new and useful Improvements in Blindstitch Sewing-Machines, of which the following is a specification.

My invention relates to improvements in blind stitch sewing machines, and in some particulars more especially to a button-hole-finishing machine for use in shoe-factories and the like.

Among the objects of my invention are to provide a work handling mechanism for a button-hole-finisher in which the work may be handled in such fashion that the stitched side of the work is uppermost, so that the operations may be best controlled by the operator; to provide a feed construction capable of high speed operation and able to handle fine leather, at high speed, without injuring the finished leather-surface; to provide a construction that will compact the threads against or into the stitched side of the leather in the course of the stitching operation; to provide improved plunger-mechanism adjustable readily, and while the machine is running, and generally and in detail to improve the construction and functioning of the work handling structure of machines of the class described.

In the drawings wherein I have illustrated an embodiment of my invention—

Figure 1 is a side elevation with parts broken away, showing some of the base-contained parts.

Fig. 2 is an enlarged detail of parts of the feeding mechanism, in association with frame parts of the machine.

Fig. 3 is a cross section through the work handling end of the machine on line 3-3 of Fig. 1, showing the plunger and beater mechanism, in association with the presser foot and clamp-plate.

Fig. 4 is a plan view of the base-carried parts of the mechanism, taken on line 4-4 of Fig. 3.

Fig. 5 is a top plan view of a presser foot structure, detached, schematically indicating the plunger and needle.

Fig. 6 is a bottom plan view of the presser foot.

Fig. 7 is a sectional elevation showing shaft connections at the right end of the

machine; section taken on line 7-7 of Fig. 1.

Fig. 8 is a horizontal section on line 8-8 of Fig. 7.

Fig. 9 illustrates perspectively the plunger adjusting means detached.

Fig. 10 indicates the clamp-plate and walking foot structure detached.

Fig. 11 is a detail of the feed-adjusting structure.

Fig. 12 is a fragment of the work.

In the drawings 20 indicates the machine base-casting, 21 the post, 22 the arm, and 23 the head. The stitch-forming mechanism herein shown, that is carried by head 23, I need not describe in detail, as it is fully described and is claimed in my copending application Serial No. 817,579 filed February 9th, 1914. It suffices here to point out that the stitch forming mechanism that I illustrate, and prefer to employ, makes a seam of the lock stitch variety, with its plane of needle reciprocation acutely inclined to the seam-length or direction of feed, and with the needle thread overcast across the surface of the work to form bights or loops each springing from the points of entrance of two successive stitches into the work and each having its bend or crest partly encompassing the point of emergence of the last made one of said stitches from the work. The head 23 carries at its lower extremity adjacent to the base 20, an upper presser foot 25 preferably rigid and stationary, and that has a suitable opening, as hereafter more fully described, through which the needle has access to the work so that the needle may enter and emerge from the front face or stitched side of the work.

The needle *n* coöperates with the rotary hook *h* and the needle thread is acted upon by a two-part looper *l* that serves to manipulate the needle thread for the formation of the overcast bights. Suitable take up mechanism, tension means, and other coöoperating elements of the stitch forming mechanism are provided, so that in the particular construction shown the entire stitch forming mechanism is an organized apparatus carried by the head and arranged to be driven cyclicly through a main gear *g* that meshes with a gear 26 on the main shaft 27 of the machine. This main shaft preferably extends longitudinally through the arm 22, and its power receiving end is provided with

pulley 28 and, preferably, with stop-motion clutch mechanism generally indicated as SM, that is operable automatically to stop the shaft always in substantially a predetermined position of rotation when the clutch controlling lever *c* is appropriately shifted. This stop mechanism *per se* forms no part of my present invention, but a suitable stop motion structure, like that suggestedly illustrated in the present drawings, is fully shown and described in my Patent No. 1,191,635, dated July 18th, 1916.

In the intended operation of this machine the work,—which may be a button-hole fly F for shoes, with a thrum T connecting the small ends of the button-holes as yet loose on the inner or flesh side of the leather, (see Fig. 12)—is positioned under the rigid presser foot 25 and fed therebeneath in a direction away from the eye of the observer in Fig. 1; and the work is lifted in nodes to be penetrated by the needle between successive feed operations, so that the needle may enter and emerge from the stitched side, or flesh side, of the work, passing below the thrum from one side thereof to the other in a plane at an acute angle to the line of thrum, and so that the overcast bights of needle thread may overlie and bind down said thrums.

For feeding or advancing the work I employ an "overhead" feed-dog or bar, that is to say, one that operates on the side of the work toward the presser foot so as to coöperate with the "flesh" side of the leather, and this feed dog or bar I arrange to be driven from the main shaft. Specifically, in the construction shown, the presser foot has made in its underside a dove tail groove 30 extending fore-and-aft or directly away from the observer in Fig. 1, at, say, a 28° angle to the plane of needle-reciprocation and in this groove is slidably mounted the "feed dog" or bar 31. This bar is in the form of a flat serrated strip that extends in rear of the presser foot and is then bent up to make a cylinder end for sliding or slot connection 32 with the operating lever 33. This lever extends up in a suitable recess in the head frame 23 to which it is pivoted as at 34 and its upper end is pivoted as at 35 to the link 36 that has its other end pivotally connected to an adjustable wrist-pin structure 37 operatively connected with the end of the main shaft 27. In the specific construction shown the gear 26 on the end of the main shaft 27 bears a fixed stud 38 that has a T shaped slot 39 in which is slidable, for radial adjustment, the head of a bolt 40. The bolt is surrounded by a sleeve 41 that may be clamped by the nut 42 against the stud-face to retain the wrist-pin structure thus formed in any desired position of radial adjustment. The end of link 36 surrounds this sleeve 41, and manifestly by radial adjustment of wrist-pin, the

length of throw of the lever 33 may be adjusted, to alter the stitch-length. Of course as the main shaft rotates the lever 33 is vibrated, sliding the feed dog 31 fore-and-aft through the slip-connection 32, and if the work be pressed against the feed bar 31 during the forward movement of the latter the work will, of course, be fed forward.

For coöperation with the feed dog, this having only a two-way motion, I provide a complementary feed member that I term the walking-foot, having positive up and down motion to bring it into or out of operative correlation with the feed dog, and preferably capable of following the forward or feeding motion of the dog 31.

In the construction shown, 45 indicates the walking foot arranged directly below the feed-dog 31, to work against the latter, the walking foot being pivoted to a vertical link 46 that in turn is pivoted to the horizontal arm of a bell crank lever 47, the vertical arm of which is connected by link 48 with a crank 49 mounted on a rock shaft 50. When shaft 50 is oscillated, obviously the walking foot is bodily raised and lowered and its positively-effected movement is supplemented by incidental movements occasioned primarily by the feed dog 31. A spring 51 connected between the lower extremity of the walking foot and the pin 52 on link 46 tends to hold the walking foot always with its upper surface substantially horizontal, and a spring 53, connected between the rear portion of the walking foot and the pin 54 on the frame, tends always to hold the foot in its forward-most position. The oscillations of the rock shaft 50 being properly timed, the walking foot 45 rises to press firmly against the under side of the work when the feed is ready to advance, and is firmly pressed against the work during the feeding movement. The arrangement of the walking foot on the vertical link 46 pivoted at both ends, enables the walking foot to coöperate with the feed-dog during the entire forward movement of the latter, and when, after the forward movement is completed, the rock shaft causes the walking foot to descend to an inoperative position, its springs 51 and 53 restore it to its normal position with respect to the link 46.

In order to clamp the work against the under side of the presser foot during the intervals when the feed is not in action, I employ a lower spring-pressed presser-foot or clamp plate 56 extending fore-and-aft beneath the stationary presser foot. This plate is carried by a vertical guide post 57 guided in the subjacent machine base 20, and it is related to the walking foot 45 in such fashion as when the latter is exerting its forcible pressure upon the under side of the work in opposition to the feed, the clamp 130

plate is moved to inoperative or depressed position so that the feed may be unresisted. For this purpose post 57, as best shown in Figs. 1 and 3, is seated at its bottom in a 5 slide block 58 sliding vertically in a recess 59 in the frame, and the pivot pin 47' for the bell crank lever 47 of the walking foot mechanism is connected to this block, which is normally sustained in raised 10 position by a strong leaf spring 60. Such spring 60 extends along the under side of the base 20 to a supporting bracket 61, where the spring fulcrums between its ends on a brace 62 and is adjustable as to tension by means 15 of the bolt 63 that may raise or lower its fastened end, beyond the fulcrum.

Now it will be apparent that as the walking foot is forced upward into contact with the feed, by an extent of motion of rock-shaft 50 in excess of that which would just produce such contact, the walking foot itself becomes the fixed point or fulcrum of the lever-system and the pivot pin 47' of the bell crank lever 47 forces downward the 25 slide block 58 against tension of spring 60, so carrying down the pressure-plate 56.

A suitable rigid presser foot, 25, may be constructed as shown in Figs. 5 and 6 to provide in its under surface a recess 70 for the 30 goods to which the needle may have access through a slot 71 alining with the path of needle reciprocation, and therefore at an acute angle, to the line of feed. In its upper surface, in the particular construction 35 shown, the presser foot may have inlaid therein a needle-guiding, hardened steel plate, 72, and it may be provided with a looper receiving recess 73 in which are made appropriate openings 73' for the two looper 40 points. Beyond the recess 70 the underside of the presser foot is made flat, as at 74, to form an anvil-surface for the beater, (to be described) to work against.

I prefer also that on the under surface of 45 the presser foot a thrum gatherer 75 be provided, such thrum gatherer, in the specific construction shown, being a shallow inverted trough, with its channel tapering toward the rear, disposed at its axis approximately parallel to the line of feed, such trough being inserted in a suitable recess in the under side of the presser foot, preferably with its edges slightly projecting below the plane of the under-side of said presser- 50 foot. The narrow throat of such gathering channel opens to the goods recess 70 very near to the portion of slot 71 where the needle co-operates with the work.

For co-operation with such thrum gatherer 55 I preferably provide on the clamp plate 56 a pressure spring 76, that is shown as a doubled leaf-spring extending out in front of the presser foot and back over the top of the plate 56, the extremity of said spring 60 being shaped to conform with the edges of

the thrum gatherer and being arranged for depression into a shallow recess 77 in the plate 56.

It will be apparent now that as the work is fed forward, thrums are gathered into line and fed forward precisely to the stitching point in a compact bundle, through the action of the thrum gatherer, that is aided by the action of the spring 76 which holds the work very closely up to the thrum 75 gatherer, even when the plate 56 is depressed, so as to minimize the chance of any loose thread escaping the action of such gatherer.

Below the needle slot 71 opening to the work recess 70 of the presser foot there works a plunger or bender 80, this being preferably a vertically guided member extending through the subjacent frame arm and having preferably a narrow end disposed crosswise to the line of needle reciprocation, to work through an opening 82 in the clamp plate 56, and into the presser-foot recess 70. The plunger, when raised, spans the needle slot 71 and the portions 70' of the 80 presser foot flanking the needle channel 71 to prevent the plunger from lifting the work too high, so that they thus act as front guides, by which the location of the work with respect to the needle path is determined 85 from the front or stitched face of the goods and the depth of penetration of the needle into the work is made uniform.

Supplementing the plunger 80 I provide a seam-beater 85, in the form of a flat ended 100 rod, working through an appropriate opening 86 in the clamp-plate 56 against the flat under surface or anvil 74 of the presser foot, this beater being preferably mounted to rise and fall with the plunger and 105 adapted on each reciprocation to deliver a blow on the previously completed stitches, so that as a result of the beater operation the stitching and thrum ends are practically pounded into the flesh side of the work, and 110 the threads are flattened, producing a very uniform and attractive finish on the stitched side of the work, as well as flattening any slight ridges on the unbroken "fair" side of the work, that may be raised by the presence of the blind-stitches in the leather.

The plunger and beater, are both mounted, adjustably if desired, on a head 88, that is arranged to be vertically reciprocated by means of a cam and roller structure, whereof the cam is driven by a rock shaft that I may term the plunger shaft; and the limits of throw of such head 88 I 115 preferably make to be variable by adjustment at the will of the operator. The adjustment devices provided are such that the operator may change the adjustment even while the machine is running and the adjusting finger-piece is positioned on the 120 front of the base 20.

The roller 89 on head 88 engages a double wall cam slot 90 in the cam 91, such slot affording a dwell, a rise and a second dwell. Shaft 92 that bears the cam 91 extends 5 lengthwise of the machine beneath the base thereof, and is mounted for bodily movement to vary the limits of the throw of the plunger that is due to the action of the cam. Thus shaft 92 is mounted in a gate, comprising 10 two end pieces 93 and 94 and the longitudinal connecting post or gate-axis 95, the latter being pivoted as at 96—96 in the frame-end on the one hand and in bearing wall 97 on the other hand, so that shaft 92 15 stands normally below and in rear of the post 95. The end arm 93 has a lever extension 98 with which co-operates an adjusting bolt 99, taking through a slot in lever 98 and opposed by a tension spring 100, the 20 head 101 of the bolt extending forward through the front wall of the base for convenient manipulation to oscillate the gate, thereby to raise or lower the plunger shaft 92. The bodily movement of the plunger 25 shaft in its gate has, however, a tendency to change the time of cam 90, and this is compensated for by the arrangement of the shafting that I will now describe.

Both of the working shafts within the 30 base, to wit, the walking foot shaft 50 and the plunger shaft 92, extend beyond the bearing wall 97 of the base, (the former shaft receiving bearing therein), and both said shafts are connected with the main 35 shaft 27 to receive motion therefrom. In the specific construction shown, the main shaft, within post 21, bears a single eccentric 105 which communicates its motion through a link 106 to a lever 107 that is connected (as best shown in Fig. 7) with the 40 extremity of shaft 50, and that also has pivotal connection, at a suitable distance from said shaft 50 as a center, with a link 108 that is connected by crank 109 with the 45 plunger shaft 92.

It will be observed with respect to Fig. 9 that, as plunger shaft 92 is lowered by the rocking of the gate on which it is carried, the "time" of the cam may remain substantially 50 unchanged. Of course, the swinging of shaft 92 downward around shaft 96 at its center tends to move the cam bodily to the right as it descends, so tending to retard the time when the cam 91 will raise the plunger; 55 this assuming that the shaft 92 were to receive no rotary displacement-incidently to its bodily movement in the gate. But, as may be noticed in consideration of Fig. 9, this bodily displacement of shaft 92 (throwing 60 it downward and to the right in Fig. 9) results in a rotative displacement of shaft 92, counter-clockwise in Fig. 9, thereby advancing the cam rotatively and so tending to maintain the cam-time substantially uni-

form with respect to the operation of the 65 main shaft.

In order that the clamp plate 56 and walking foot 45 may be lowered readily to permit of insertion of the work, a lever 110 may be pivoted at 111 as shown in Fig. 2 70 for operation by a "knee-lift" link 112 to depress the spring 60 that normally holds up the stated parts to their work. This lever may also be caused to work the clutch shifter, for the stop motion device SM, but 75 as its connections for this purpose are of no importance to the present application I have omitted the same.

While I have herein described in some detail a particular embodiment of my invention for purposes of full disclosure it will be apparent to those skilled in the art that many changes might be made in details of construction and arrangement without departure from the spirit and scope of my 85 invention and within the scope of the appended claims.

Having described my invention, what I claim is:

1. In a blind stitch sewing machine, the 90 combination of a frame providing a presser foot having an opening to permit co-operation of the needle with the work, stitch forming means above said presser foot including a reciprocating needle, plunger 95 means below said presser foot to elevate the work into stitch-receiving relation to the needle, and work feeding mechanism comprising a feed member arranged on the same side of the work as the presser foot and having only a fore-and-aft movement, a walking foot below the work and means to give said walking foot an up and down movement only, said walking foot being free to follow the advancing movement of the feed 100 when elevated by its moving means.

2. In a blind stitch sewing machine the combination of a frame, a presser foot, carried thereby having an opening to give the needle access to the work therebelow, stitch forming mechanism above said presser foot including a reciprocating needle, plunger mechanism below said presser foot for elevating nodes of the work to the action of the needle, and feeding mechanism comprising 110 a sliding feed-member mounted in the under side of the presser foot, means to reciprocate said feed-member, a walking foot on the same side of the work as the plunger, means to raise and lower said walking foot, said walking foot being free with respect to said means to follow the advancing movement of the feed while the walking foot is raised, and means normally to clamp the work 115 against the under side of the presser foot, 120 associated with said walking foot to be depressed when the walking foot is positively raised.

3. In a blind stitch sewing machine, the combination of a frame providing an overhanging arm, a head, stitch forming mechanism carried by said head, a presser foot below said stitch forming mechanism, a sliding feed member mounted in the under side of said presser foot, a shaft for driving said stitch-forming mechanism mounted in said arm and having a crank, and means for connecting said sliding feed-member with said shaft comprising a lever having connection with said feed-member and having connection with a crank on said shaft.

4. In a blind stitch sewing machine, the combination of a frame providing an overhanging arm, a head, stitch forming mechanism carried by said head, a presser foot below said stitch forming mechanism, a sliding feed member mounted in the under side of said presser foot, a shaft for driving said stitch-forming mechanism mounted in said arm and having a crank, and means for connecting said sliding feed - member with said shaft comprising a lever connected with said feed and a wrist pin carried by said shaft and adjustable radially with respect thereto, said wrist pin having connection with said lever.

5. In a machine of the character described the combination of a presser-foot, a plunger therebelow, a rock shaft for operating said plunger, and means for bodily moving said rock shaft to vary the limits of throw of the plunger.

6. In a machine of the character described the combination of a frame, a presser foot, a plunger below said presser foot, means for vertically reciprocating said plunger including a rock shaft, means for bodily adjusting said rock shaft to vary the limits of throw of the plunger, said means including an adjusting member extending to the front of the frame for operation exteriorly to the frame.

7. In a blind stitch sewing machine the combination of work handling means including a plunger, means to reciprocate said plunger including a rock shaft, means for bodily moving said rock shaft to vary the limits of throw of the plunger, and means to vary the limits of throw of the rock shaft to maintain substantially uniform the time of the plunger at different adjustments of throw.

8. In a machine of the character described the combination of a main shaft, a plunger operating rock shaft, pivotally adjustable means carrying said rock shaft for bodily displacement, a plunger operatively associated with said rock shaft for variation of its limit of throw in accordance with the position of the rock shaft, and means connecting said rock shaft with the main shaft operable to vary the limit of throw of the rock shaft to maintain substantially uniform time of

the plunger, under different bodily positions 65 of the rock shaft.

9. In a machine of the character described work handling mechanism comprising in combination a plunger, a plunger operating rock shaft, a cam carried by said rock shaft 70 associated with the plunger, means supporting said rock shaft for bodily pivotal displacement, means accessible from the exterior of the machine for adjusting the last said means, to bodily displace the rock shaft 75 for varying the limits of throw of the plunger, a main shaft, driving connections between said main shaft and the rock shaft, operable to vary the limits of throw of the rock shaft under different bodily adjustments of the rock shaft, to tend to maintain constant the time of the plunger.

10. In a machine of the character described, a base, a presser foot, a plunger, a work feeding part, shafts for said plunger 85 and for said work feeding part in said base, a pivoted gate supporting said plunger shaft for bodily displacement to vary the limits of throw of the plunger, and means for operating said two shafts, a lever fast 90 on said shaft for the work feeding part, a crank on the plunger shaft, a link between said lever and crank accommodating the bodily movements of the plunger shaft, and means to vibrate said lever.

11. In a button-hole finishing machine, a plunger, a presser-foot having a work receiving recess in its underside, and a needle-opening communicating with the recess, and a thrum gatherer comprising a tapering 100 channel, opening to said recess.

12. In a button-hole finishing machine, a plunger, a presser-foot having a work receiving recess in its underside, and a needle-opening communicating with the recess, and a thrum gatherer comprising a tapering 105 channel, opening to said recess and a channel formed in a trough inserted in a recess in the presser-foot, with its converging edges projecting below the plane of said presser-foot.

13. In a machine of the character described, the combination of a presser-foot having a thrum-gathering channel, a clamp plate opposed to the presser foot, means to 115 move said clamp plate, and a spring structure carried by the clamp plate opposing the thrum channel.

14. In a machine of the character described, means for presenting the work in 120 bent position, stitch forming means including a needle disposed to enter and emerge from the same side of such bent work, and means for beating the pre-formed stitches.

15. In a blind stitch sewing machine, the combination of work handling means arranged to present the work in bent position 125 and to feed the work, stitch forming means

- arranged to form blind stitches entering and emerging from the same side of the bent work, and seam-beating means arranged in rear of the bending means with respect to the direction of feed.
- 5 16. In a machine of the character described, the combination of a presser foot, blind-stitch forming means above the same, arranged to work through the presser foot to enter and emerge from the upper surface of the work, a beater below the presser foot arranged to strike the work below the pre-formed stitches, and means to operate said beater.
- 10 17. In a machine of the character described, the combination of a presser foot having an opening, stitch forming mechanism on one side of said presser foot, a plunger on the other side of said presser foot, a beater in rear of said plunger in the direction of feed, and means to operate the beater and plunger.
- 15 18. In a machine of the character described, the combination of a presser foot having an opening, stitch forming mechanism on one side of said presser foot, a plunger on the other side of said presser foot, a beater in rear of said plunger in the direction of feed, and adjustable means to reciprocate the plunger and beater in unison. 25
- 20 19. Work presenting mechanism for sewing machines comprising a reciprocable bender having a cam-engaging member, a cam and cam shaft, and means for adjustably supporting the same and means for actuating said cam shaft. 30

In testimony whereof I hereunto set my hand in the presence of two subscribing witnesses.

JAMES WHITELAW.
